(57) CLAIM

The ornamental design for a disposable container for ready-made cocktail, as shown and described.

DESCRIPTION

FIG. 1 is a front perspective view of the disposable container for ready-made cocktail of the present invention showing my new design;

FIG. 2 is a front elevational view thereof;

FIG. 3 is a back view thereof;

FIG. 4 is a right side view thereof;

FIG. 5 is a left side view thereof;

FIG. 6 is a top plan view thereof; and,

FIG. 7 is a bottom plan view thereof.

The broken lines are for the purpose of illustrating portions of the article that form no part of the claimed design.

1 Claim, 4 Drawing Sheets
